UNITED STATES PATENT OFFICE.

WILLIAM H. ODELL, OF YONKERS, NEW YORK.

STEAM-BOILER.

SPECIFICATION forming part of Letters Patent No. 376,205, dated January 10, 1888.

Application filed January 18, 1887. Serial No. 224,668. (No model.)

To all whom it may concern:

Be it known that I, WILLIAM H. ODELL, of Yonkers, Westchester county, in the State of New York, have invented a certain new and 5 useful Improvement in Steam-Boilers, of which the following is a specification.

The invention applies to all that class of steam-boilers, whether known as "sectional" or otherwise, in which a large part of the heating-surface is in the form of tubes arranged to receive heat on their exteriors and to generate 10 a current of air and steam flowing rapidly along the interiors of the several pipes, which are usually placed inclined to favor the circulation, the water and steam rising through 15 one series of headers and the water descending through another series at the other ends of the tubes. It is common in this class of boilers to employ a drum which is known as the "steam and water drum," or "separating-drum," which lies above the heating-tubes and receives 20 the ascending current of steam and water at one end and allows the water to descend from the other end. The steam is taken from 25 the upper side of this steam and water drum at or near the delivery end and is led away to be used for power or for other purposes, as heating.

It is important to take the steam from the 30 back or delivery end of the drum, so that the vigorous movement of the steam from front to rear shall aid in moving the water in that direction. As heretofore worked under such arrangement, the steam is liable to drive the 35 water toward the rear too strongly, banking it up at the rear, so as to give water instead of steam, or to give too wet steam to the steam-pipe. This is more especially the case when a sudden demand is made on the boiler, as in 40 the case of a rolling-mill engine when a large mass of iron is in the rolls and the great resistance calls for much steam to maintain the speed.

My invention is intended to avoid the difficulty and give dry steam while taking the steam from a point at or near the rear end of the drum and maintaining an active circulation of the water from front to rear of the drum. I place the drum with the receiving 45 end low and the delivering end high. The inclination should be such that when the water

is at the ordinary level it will about fill the receiving end and only allow a sufficient depth at the other end to insure the delivery of the water into the downtakes, so as to maintain 55 a circulation.

The following is a description of what I consider the best means of carrying out the invention.

The accompanying drawing forms a part of 60 this specification, and is a central vertical section in the plane of the axis of the drum.

Referring to the drawing, and to the letters of reference marked thereon, A is the brick-work or other substantial material inclosing a 65 space which serves as the furnace.

B is the grate.

D represents a set of tubes of uniform size, arranged to extend through the furnace in an inclined position, with provisions for circulating the flame and hot gases from the fire thoroughly between the several tubes, so as to impart heat thereto and produce steam 70 therein.

C are the headers through which the water 75 descending through the downtakes c from the delivering end of the drum obtains access to the lower ends of these tubes, and E are the headers through which the steam produced in the tubes rises, accompanied by water, which is 80 dragged along therewith.

G is the separating-drum or steam and water drum. It is mounted in the inclined position shown. The delivering end G², which delivers the steam from its upper side into the 85 steam-pipe I and delivers the water from its lower side through the downtakes c into the descending headers C, is higher than the other end, G', the difference in level being nearly the whole diameter of the drum. 90

It will be understood that gage-cocks or try-cocks, or any suitable form of water-gage or other ordinary or suitable means, may be employed to determine the water-level in the boiler. This should be such that when making steam actively the water is disengaged 95 from the steam in the liberal water-surface presented and is delivered freely into the headers C, through which it descends; but there is but little depth of water at that end, 100 (the delivering end) of the drum. The other end of the drum is nearly filled with water.

The steam has the ordinary opportunity to disengage itself from the water over the whole of the surface presented. The steam flows vigorously toward the delivering-pipe I, with a strong tendency to drag the water along therewith. This tends to hold the water in the drum at an inclination. The inclination may coincide exactly with that of the axis of the drum, or it may vary somewhat one way or the other therefrom; but the inclination greatly reduces the chance that the water shall become banked up at the delivering end and shall there fill the drum so as to deliver water into the steam-pipe I.

15 Modifications may be made in the details. I can place side by side a number of the drums G, each connected by headers C and E to the tubes D. The tubes may be changed in size and in number. The headers may be variously formed and connected. I prefer to adopt the arrangement and proportions shown in the patent to J. B. Root, August 5, 1884, No. 302,944, except that the drum G is placed with

its delivering end so much higher than the receiving end that mischief from the banking 25 of the water in the delivery end is effectually avoided.

I claim as my invention—

In a steam-boiler, the tubes D and headers C E, connected together and to a drum, G, in 30 combination with each other and with a steam-delivery connection, I, the drum being arranged with its rear or water-delivery end higher than its front or steam and water receiving end, and the steam-pipe I being arranged to take the steam from the drum at a point near the rear end, all substantially as herein specified.

In testimony whereof I have hereunto set my hand, at the city of Yonkers, New York, 40 this 15th day of January, 1887, in the presence of two subscribing witnesses.

W. H. ODELL.
